D. C. DAVIS.

LID CLOSING AND HOLDING DEVICE FOR JOURNAL BOXES.

APPLICATION FILED JAN. 5, 1920.

1,360,194.

Patented Nov. 23, 1920.

UNITED STATES PATENT OFFICE.

DONALD C. DAVIS, OF BUFFALO, NEW YORK, ASSIGNOR TO GOULD COUPLER COMPANY, OF NEW YORK, N. Y.

LID CLOSING AND HOLDING DEVICE FOR JOURNAL-BOXES.

1,360,194.

Specification of Letters Patent. Patented Nov. 23, 1920.

Application filed January 5, 1920. Serial No. 349,391.

To all whom it may concern:

Be it known that I, DONALD C. DAVIS, a citizen of the United States, residing at Buffalo, in the county of Erie and State of New York, have invented a new and useful Improvement in Lid Closing and Holding Devices for Journal-Boxes, of which the following is a specification.

This invention relates to spring-actuated devices which are used on the lids of car journal boxes for closing the lids and releasably holding the lids in their closed and open positions.

The lids of car journal boxes are usually provided with leaf springs or spring-actuated levers, which press against the hinge lugs at the top of the boxes in such a way as to releasably hold the lids either closed or open. In some boxes the leaf spring or lever extends up into a recess in the underside of the hinge lug and presses outwardly against the front wall of the recess for holding the lid closed. In opening the lid the spring or lever passes around the lower end or corner of the hinge lug and bears against the outer face of the lug for holding the lid in the raised, open position. The spring must be relatively stiff in order to tightly close the lid, and since the upper end of the spring or lever must have considerable movement in order to pass around the corner of the lug in opening and closing the lid, such springs are frequently broken or become permanently set and are, therefore, a source of trouble and expense. The spring actuated lever closing and holding devices as heretofore constructed are more or less complicated and add materially to the cost of the boxes.

The objects of this invention are to provide a practical and desirable lid closing and holding device, which is of simple and inexpensive construction, which can be applied to the lids with the minimum labor and expense and which, while giving a strong spring action to the device, permits a free, extended movement of the same; also to provide a lid closing and holding device which enables the use of a substantially flat lid free from outwardly projecting portions; also to provide a closing and holding device of this sort in which the action of the operating spring can be readily adjusted to increase or decrease the pressure of the holding lever as may be required.

In the accompanying drawings:

Figure 1 is a fragmentary sectional elevation of a journal box and lid provided with a lid-closing and holding device embodying the invention, showing the lid closed.

Fig. 2 is a similar view thereof, showing the lid held in its open or raised position.

Fig. 3 is an inside elevation, partly in section, showing the lid closing and holding device.

A represents the journal box, the outer end portion only of which is shown, and B the lid for closing the filling opening a of the box. The lid is hinged at its upper end to swing outwardly and downwardly, preferably, as usual, by a hinge pin c passing through hinge lugs on the lid and through a hinge lug D on the journal box above the filling opening.

In the embodiment of the invention herein described, the spring-actuated lid closing and holding device comprises a lever 10, which is located on the inner side of the lid and is suitably pivoted at its lower end on the lid near the lower end thereof with its upper end arranged to bear against the hinge lug D, and a coil spring 11, which is arranged between the lever and a stud or member 12, which projects inwardly from the lid, so as to press the upper end of the lever outwardly or toward the lid. The upper end of the lever is suitably rounded or shaped to properly enter the recess d in the hinge lug D and engage and slide on the hinge lug, and the lever is preferably made with strengthening flanges to give a light but strong lever. In the construction shown, the lower end of the lever is pivoted on a pin 13 which passes through a hole in the lower end of the lever and through a pair of perforated lugs 14 extending inwardly from the lid at opposite sides of the lever. The pivot pin is preferably retained in place by a cotter pin or other retainer 15 which enables the ready removal of the pivot pin. The stud or member 12 is preferably a bolt of the ordinary carriage bolt type having a rounded or convex head and a shank portion 16, of square or non-circular shape adjacent the head, which passes through and fits in a correspondingly shaped hole in the lid B. The bolt passes loosely through a hole in the lever 10 and is provided at its inner end with a washer, disk or bearer 17, which is retained on the bolt by

an ordinary nut 18, or in any other suitable manner. The spring 11 surrounds the bolt between the lever and the washer 17. Preferably, the lever is provided with a circular seat or socket 19, in which the outer end of the spring is confined, and the washer or disk 17 is provided with a central boss which extends into the inner end of the spring. The spring is thus retained in position concentrically with the bolt 12 between the lever and the washer or disk 17. The pressure of the spring and the pressure of the lever against the hinge lug can be regulated as desired, by tightening or loosening the nut 18 by means of an ordinary wrench or tool.

10 The lid-closing and holding device constructed as described is simple and inexpensive and can be quickly applied to the lid with very little labor, and in the case of the 20 loss or breakage of any of the parts, they can be quickly and easily replaced by an unskilled workman without the use of special tools.

25 In the closed position of the lid the spring presses the upper end of the lever 10 outwardly against the front wall of the recess *d* in the hinge lug *D*, thus drawing the lid inwardly against the rim of the filling opening and holding it firmly but yieldingly in 30 its closed position. The lid can be raised as usual, by pulling upwardly and forwardly on its lower end with sufficient force to overcome the holding action of the spring-actuated lever. As the lid is being raised, the 35 upper end of the lever will pass around the lower end of the hinge lug, and bear against the outer face of the lug, as indicated in Fig. 2, thereby holding the lid in its open position. In this position the closing and holding 40 device is readily accessible and can be easily adjusted or replaced by a new one.

I claim as my invention:—

1. The combination with a journal box, and a lid hinged thereto, of a lever pivoted 45 on said lid and having a free end arranged to bear against a part of the journal box, a member which extends inwardly from the lid beyond said lever, and a spring arranged inwardly beyond the lever between 50 said member and said lever and acting on the lever to force the free end thereof against said part of the box.

2. The combination with a journal box, and a lid hinged thereto, of a lever pivoted 55 at one end on the lid and having its opposite end arranged to bear against a part of the journal box, a detachable member which extends inwardly from the lid, and a spring arranged between said member and said lever and acting on the lever between its pivot 60 and the free end of the lever to force said free end toward the lid.

3. The combination with a journal box, and a lid hinged thereto, of a lever pivoted 65 on said lid and having a free end arranged

to bear against a part of the journal box, a member which extends inwardly from the lid beyond said lever, a spring arranged inwardly beyond the lever between said member and said lever and acting on the lever 70 to force the free end thereof against said part of the box, and adjustable means for regulating the force exerted by said spring.

4. The combination with a journal box, and a lid hinged thereto, of a lever pivoted 75 on said lid and having a free end arranged to bear against a part of the journal box, a stud which projects inwardly from the lid beyond said lever, a spring bearer on said stud inwardly beyond said lever, and a 80 spring which surrounds said stud between said bearer and the lever and acts to force the free end of the lever against said part of the box.

5. The combination with a journal box, 85 and a lid hinged thereto, of a lever pivoted on said lid and having a free end arranged to bear against a part of the journal box, a stud which projects inwardly from the lid beyond said lever, a spring bearer adjustable on said stud inwardly beyond said lever, and a spring which surrounds said 90 stud between said bearer and the lever and acts to force the free end of the lever against 95 said part of the box.

6. The combination with a journal box, and a lid hinged thereto, of a lever pivoted on said lid and having a free end arranged to bear against a part of the journal box, a bolt which extends inwardly through the lid 100 and through said lever, a nut screwed on the inner end of said bolt, and a spring surrounding the bolt between said nut and the lever and acting to force the free end of the lever against said part of the box.

7. The combination with a journal box, and a lid hinged thereto, of a lever pivoted on said lid and having a free end arranged to bear against a part of the journal box, a bolt which extends inwardly through the lid 110 and through said lever and is held from turning in the lid, a nut screwed on the inner end of said bolt, and a spring surrounding the bolt between said nut and the lever and acting to force the free end of the lever 115 toward the lid.

8. The combination with a journal box, and a lid hinged thereto, of a lever pivoted on said lid and having a free end arranged to bear against a part of the journal box, a detachable member extending inwardly through said lid and said lever, and a spring on the inner end of said detachable member and acting to force the free end of said lever 120 against a part of said journal box.

9. The combination with a journal box, and a lid hinged thereto, of a lever pivoted on said lid and having a free end arranged to bear against a part of the journal box, and an adjustable and readily detachable 130

member extending inwardly through said lid and said lever, and a spring on said adjustable and detachable member and acting to force the free end of said lever against 5 a part of said journal box.

10. The combination with a journal box and a lid hinged thereto, of a lever detachably pivoted to said lid for movement toward and from said lid to releasably engage 10 a part of the journal box, a removable bolt having a seating in said lid and extending inwardly through said lever, a spring surrounding said bolt inwardly of said lever, and an adjustable bearer on said bolt for 15 maintaining spring pressure on said lever.

11. The combination with a journal box and a lid hinged thereto, of a lever detach-

ably pivoted to said lid for movement toward and from said lid to releasably engage a part of the journal box, a removable 20 bolt having a seating in said lid and extending inwardly through said lever, a spring surrounding said bolt inwardly of said lever, and an adjustable bearer on said bolt for maintaining spring pressure on said 25 lever, said adjustable bearer member having a part seated in one end of said spring for centering said bolt in said spring.

Witness my hand this 30th day of December, 1919.

DONALD C. DAVIS.
